[57] CLAIM

The ornamental design for a stamp dispenser, as shown and described.

DESCRIPTION

FIG. 1 is a front view of the stamp dispenser of the present invention;

FIG. 2 is a right side view;

FIG. 3 is a rear view;

FIG. 4 is a top view;

FIG. 5 is a bottom view; and,

FIG. 6 is a left side front perspective view.

The stamp roll structure depicted by means of broken lines in FIG. 2 has been shown for illustrative purposes only and forms no part of the claimed design.
